[57] CLAIM

The ornamental design for a storage rack for cleaning supplies, as shown and described.

DESCRIPTION

FIG. 1 is a top, front, and left side perspective view of a storage rack for cleaning supplies showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof, the left side being a mirror image of that shown; and

FIG. 7 is a vertical cross-sectional view thereof, taken along line 7—7 of FIG. 4.
